UNITED STATES PATENT OFFICE.

ELNATHAN PHELPS, OF HARTFORD, MICHIGAN.

COMBINED FANNING-MILL AND COCKLE-SEPARATOR.

SPECIFICATION forming part of Letters Patent No. 317,412, dated May 5, 1885.

Application filed December 19, 1884. (No model.)

To all whom it may concern:

Be it known that I, ELNATHAN PHELPS, a citizen of the United States, residing at Hartford, in the county of Van Buren and State of Michigan, have invented certain new and useful Improvements in Combined Fanning-Mills and Cockle-Separators; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention has for its object to provide an improved novel and simplified construction of combined fanning-mill, grain-separator, and cockle-machine; and my improvements consist, essentially, of the details of construction and general arrangement of parts, all as will be hereinafter fully described, and the features of novelty specifically designated in the claim.

In the accompanying drawings, Figure 1 represents a side elevation, in partial section, of my complete invention; Fig. 2, a transverse section of the same, taken on the line $x-x$ of Fig. 1. Fig. 3 represents an end view, and Fig. 4 a detail sectional view above the cockle-rollers.

Similar letters of reference occurring on the several figures indicate corresponding parts.

Referring to the drawings, A represents the main frame of my improved apparatus, which is provided at one end with a suitable fan-chamber, B, and upon the top with a suitable hopper, C, as shown, said hopper being provided with the slide a , to regulate the flow of grain to the screens.

D represents the pulley, which, connected by the belt b to pulley B' , communicates motion to the fan E in the chamber B in the usual manner.

F represents the first or upper screen, to which the grain is delivered from the hopper C, and which is located above the slanting dead-bottom or conductor F'.

G represents the next succeeding screen, located above the dead-bottom or conductor G', and H represents the last or bottom screen, all of said screens slanting to the open end of the machine, while the dead-bottoms or con-

ductors slant toward the interior central portion of the same, as fully shown in Fig. 1. All of the screens are vibrated by means of the 55 crank-arm I, projecting from the crank-shaft d of the pulley D, and the springs e , arranged one on each side of the base of the machine, as shown.

Beneath the lower screen, H, is provided a 60 hopper, f, which stands above the longitudinally-arranged inclined rollers K, which are preferably constructed of heavy sheet-iron, having a series of small depressions or hollows upon their entire surfaces, which are adapted 65 to receive the largest-sized cockle, but not large enough to receive the kernels of wheat.

Between the two rollers K is arranged an inclined distributing-board, g, having a sharp and raised center, so as to press the wheat to 70 the faces of the rollers until the cockle is taken up by the depressions in said rollers and discharged into the chamber J beneath, while the clean grain passes down the inclined distributing-board g and is discharged through the 75 spout K'. The cockle is discharged from the chamber J through the spout J', by means of the spiral conveyer L, in a manner well known. The rollers K are revolved by means of the gear-wheels M M', through the medium of the 80 bevel-gear N', which meshes with a similar gear, N, upon the shaft h of the pulley O, said pulley O being connected by a suitable belt, i, to the pulley j upon the main driving-shaft d . The spiral conveyer L is revolved by means of 85 the spur-wheel k, actuated by the endless chain l upon the same and upon the gear-wheel M, as fully shown in Fig. 3.

In the operation of my invention the wheat or other grain first passes down from the hopper C upon the first screen, F, which carries over all straw or coarse matter, the grain falling through said screen upon the inclined dead-bottom or conductor F', where it is subjected to a blast through the valve m , which carries 90 away all fine dust, the blast being regulated by said valve to suit different kinds of grain. The grain next falls in a thin sheet upon the screen G, meeting with a stronger blast through the valve n , which is regulated according to 95 the grain handled. From screen G the grain drops down upon the dead-bottom or conductor G', which carries it back to the blast from valve o, at which point both of the valves n and o are 100

so regulated that both blasts can be brought to bear on the grain in its transit from screen G to the dead-bottom or conductor G', thereby removing all heavier foreign matter that has not already been carried off. From the conductor G' the grain is carried in a thin sheet to screen H, at which point the valve o may be regulated to conduct another blast to the moving grain. The grain from the screen H is delivered into the hopper f, thence to the distributing-board g, between the two rollers K, the cockle being taken up by the depressions in said rollers and discharged from the machine, the cleaned grain passing down the distributing-board g, and out of the discharge-spout K', as already above first described.

Beneath the hopper f, on each side, and above the rollers K, are situated longitudinal scrapers s, which are adapted to impinge upon the said rollers in such manner that if a kernel of grain should happen to lodge in the de-

pressions in the face of the rollers said scrapers would dislodge the grain and throw it back upon the distributing-board g.

Having thus described the construction and operation of my invention, I claim as new and useful—

The herein-described combined fanning-mill and cockle-separator, comprising the frame A, provided with the fan-chamber B, fan E, hopper C, screens F, G, and H, conductors F' G', valves m, n, and o, hopper f, rollers K, distributing-board g, conveyer L, and the gear-wheels and driving-pulleys, substantially as and for the purpose specified.

In testimony whereof I affix my signature in presence of two witnesses.

ELNATHAN PHELPS.
